ELECTRIC-DISCHARGE DEVICE AND CATHODE

Kenneth J. Germeshausen, Newton Center, and Seymour Goldberg, Lexington, Mass., assignors to Edgerton, Germeshausen & Grier, Inc., Boston, Mass., a corporation of Massachusetts

Application April 25, 1956, Serial No. 580,551

13 Claims. (Cl. 313—212)

The present invention relates to electric-discharge devices and cathodes therefor, and, more particularly, to improved cathode structures for use in gaseous-discharge tubes and the like.

Various approaches have been proposed for solving the problem, particularly associated with high-power gaseous-discharge devices and the like, such as hydrogen thyratrons that switch, pulse or key high-voltage circuits, of providing a cathode of small physical dimensions that, nonetheless, has a large electron-emissive surface area. Several types of cathode configurations have been evolved to try to accomplish this end, including the utilization of a plurality of parallel cathode-element electron-emitting surfaces disposed within a cup.

It has been found, however, that all portions of such cathode elements do not actually effectively emit electrons toward the anode of the discharge device at the instant that a sudden electrical discharge is initiated in the switching or keying circuits, before mentioned, and is applied to the discharge device. Once such an electrical discharge is initiated, the current flowing between the anode and cathode rises very rapidly to its final value; but, since a finite time is required for the plasma to penetrate to all regions of the cathode, most of the electrons are drawn from the portion of the cathode nearest to the anode. Operation at high pulse repetition rates results in relatively rapid deterioration of the cathode. After the current in the discharge device reaches its final value, moreover, there is a voltage drop in the gas of the device that causes a non-uniform distribution of current to be drawn from the cathode, whereby most of the current continues to be drawn from those portions of the cathode nearest to the anode. We have found, accordingly, that improved operation can be had with cathode elements of limited length, the emitting surfaces of which are more uniformly utilized. A preferred substantially optimum length L of cathode element has been selected that represents a compromise between the provision of a large electron-emissive surface area and the effecting of more uniform utilization of the cathode-emitting surface. That length L , measured in the direction between the cathode and anode, is given substantially by the following equation:

$$L = \frac{1}{2} \sqrt{\frac{2i_T R_0}{P \left(E_p - \frac{dV_s}{dx} \right)}}$$

where R_0 is the specific resistance at the electron-emitting surface, having a nominal value of four ohm-centimeters squared; i_T is the total current discharged cumulatively to the anode in the discharge device; E_p is the electrical field in the plasma between the anode and the cathode, having a nominal value of fourteen volts per centimeter; V_s is the potential drop across the cathode sheath;

2

is the potential gradient in the cathode sheath with a nominal value of —7 volts per square centimeter; and P is the total perimeter of the cathode in a plane substantially parallel to the surface of the anode.

We have therefore heretofore proposed the utilization of cathode elements having the above length or height L in the direction from the cathode to the anode and each comprising a thin enclosure housing heater windings therein and containing electron-emissive external coatings. Such cathode structures have been found to operate admirably well. There are cases, however, where the utilization of a plurality of heater elements, one for each of the cathode elements, is undesirable, and where the thermal variation inherent in this type of cathode structure over the complete cathode must be held within more uniform limits.

It is an object of the present invention, accordingly, to provide a new and improved cathode that eliminates the necessity for a separate heater winding for each of the cathode elements and that provides for a greater uniformity in temperature variations over the complete cathode area.

A further object is to provide an improved cathode structure that inherently is capable of providing greater electron-emissive area than the above-described cathodes.

A further object is to provide a new and improved electric-discharge device operating with such an improved cathode.

Other and further objects will be explained hereinafter and will be more particularly pointed out in the appended claims. In summary, however, the present invention resides in the provision of a cathode comprising a base member carrying a plurality of spaced vanes each having electron-emitting surfaces extending along a direction away from the base member, with the base member alone provided with heating means for uniformly heating all of the cathode-vane elements. Preferred constructional details are hereinafter explained.

The invention will now be described in connection with the accompanying drawing, Fig. 1 of which is a longitudinal section of an electric-discharge device embodying the invention in preferred form;

Fig. 2 is a perspective view, upon an enlarged scale, of a portion of the cathode of Fig. 1; and

Figs. 3 and 4 are similar views of modified cathode constructions.

Referring to Fig. 1, an electric-discharge device, illustrated as of the thyratron type, comprises a sealed envelope 21 containing an inverted cup-shaped anode 1, a control-grid cylinder, fragmentarily illustrated at 3 as provided with a plurality of apertures 5 in line with the anode 1, and a cathode 2. The envelope 21 may be of glass or other vitreous material and the like, being filled with an ionizable medium such as hydrogen gas. The cathode 2 is contained within an upwardly disposed conductive cup 9 containing a flat, hollow base member 11. The base member 11 is in electrical contact with the cup 9 and an external heat-radiation shield 7, the upper inward peripheral projection 50 of which serves also as a sputter shield. The base member 11 supports or carries upon its upper surface a plurality of thin substantially planar conducting vanes 13, 15, 17, etc., welded or otherwise secured to the upper surface of the base member 11. These vanes 13, 15, 17, etc. are shown confined within the cup 9 and extending toward the upper opening of the cup 9 along the direction from the cathode 2 to the anode 1, substantially perpendicular or normal to the upper surfaces of the base 11 and the anode 1. The vanes are preferably substantially equally spaced from one another. While only a few vanes are illustrated in the drawing, it is to be understood that a large number of vanes may be employed. Though the vanes are shown of substan-

tially rectangular peripheral shape, moreover, they may also assume other configurations, as hereinafter described.

Within the hollow of the base member 11 is disposed a continuous heater-coil winding 19, preferably uniformly arranged to establish substantially uniform heating along the upper surface of the base member 11. The lateral flat surfaces of the thin vanes 13, 15, 17, etc. are coated with electron-emissive material.

The anode 1 may be supported within the envelope 21 by a wire 23 which may extend through a seal 25 at the top of the envelope 21 to provide an external anode terminal for connection to the positive terminal of a source of voltage in a suitable well-known pulsing or other circuit hereinafter discussed. The cathode structure 2 may be supported by conductive strut members 27 and 39 which connect to terminal posts 31 and 33, respectively, extending through the re-entrant glass press 35 at the base of the envelope 21. Negative potential may be applied to the cathode 2 through external conductors 37 that communicate with the terminal posts 31 and 33. The ends of the heater winding 19, not shown, may be connected to supporting conductors 39 and 41 which extend to terminal posts 43 in the press 35 to receive heater current from the external leads 47. The heater winding may be maintained at cathode potential by means of the diagonal conducting strut 49 between the conductor 39 and the conductor 29. A suitable circuit for operating this discharge device is disclosed, for example, in United States Letters Patent No. 2,592,556, issued April 12, 1952, to Kenneth J. Germeshausen, and in which a source of high voltage is discharged between the anode 1 and cathode 2 under the control of an impulse fed to the grid 3.

With the aid of the above construction, but a single heater is required for all of the cathode-emitting surfaces of the vanes 13, 15, 17, etc. This permits the vanes to be extremely thin, say of the order of 0.02 inch in thickness, and hence permits the utilization of a large number of vanes within a small cathode cup, resulting in a very large effective electron-emitting surface area. A very much greater effective cathode-emitting surface area can thereby be obtained than with the aid of individually heated cathode elements. The vanes, furthermore, may be very closely spaced from one another, with spacings of the order of from 1 to 2 millimeters, more or less. Since, as before stated, the top portions of the cathode vanes are closer to the anode 1, they will normally emit more electrons than the lower portions of the vanes. In accordance with the present invention, however, the heating is effected at the bottom of the vanes so that the lower portion of the vanes will be heated more than the top portions. The free top portions, in addition, can more rapidly dissipate heat. This temperature variation along the vanes is thus the inverse of the electron-emission tendency and tends to compensate for the same, providing more uniform emission completely over the surfaces of the vanes, thereby extending materially the life of the cathode. The structure of the present invention, moreover, in view of the solid connection of the vanes to the base member 11 and the utilization of the single heater winding 19 in the base member 11, is more rugged than the before-described prior-art cathode structures.

The preferred length or height L of the vanes in the direction from the base member 11 to the anode 1 has before been discussed. Since this length or height is kept as small as possible, consistent with the above-mentioned limitations, it is desirable, in order to obtain a large emission surface area, that the other dimension of the vanes, namely, what might be termed the width of the vanes across the cathode cup 9, be very much longer than the length or height L.

The cathode of the present invention is, of course, useful in other-than the particular hydrogen discharge device before referred to. It may, as by two further illustrations, be employed in gaseous diodes or thyratrons of

other construction. Other cathode-cup or base configurations and structures may also be employed. As before stated, in addition, it is not necessary that the vanes be of rectangular configuration as discussed in connection with the embodiments of Figs. 1 and 2. They may, for example, be of other configuration, such as in the form of the concentrically and coaxially disposed annular or cylindrical vanes 13', 15', 17', etc., Fig. 3, carried by the circular base member 11' containing therein the heater element 19' and supported within the cylindrical shield 7'. As another example, the vanes may be constructed in honey-comb form to provide still a greater effective cathode-emission area. Such honey-comb vane units are illustrated at 51 in Fig. 4.

Further modifications will occur to those skilled in the art and all such are considered to fall within the spirit and scope of the invention as defined in the appended claims.

What is claimed is:

1. An electric-discharge device having a plurality of electrodes including an anode and a cathode spaced from one another along a predetermined direction within an ionizable medium, the cathode comprising a base member carrying a plurality of spaced vanes having electron-emitting surfaces extending substantially along the predetermined direction from the base member and extending substantially completely across the base member, the anode having a surface co-extensive with the complete plurality of cathode vanes for cooperating therewith, and means for heating the base member.

2. An electric-discharge device having a plurality of electrodes including an anode and a cathode spaced from one another along a predetermined direction within an ionizable medium, the cathode comprising a base member carrying a plurality of spaced vanes having electron-emitting surfaces extending substantially along the predetermined direction from the base member a distance less than the other dimension of the vane surfaces and extending substantially completely across the base member, the anode having a surface co-extensive with the complete plurality of cathode vanes for cooperating therewith, and means for heating the base member.

3. An electric-discharge device having a plurality of electrodes including an anode and a cathode spaced from one another along a predetermined direction within an ionizable medium, the cathode comprising a base member carrying a plurality of spaced substantially rectangular vanes having electron-emitting surfaces extending substantially along the predetermined direction from the base member and extending substantially completely across the base member, the anode having a surface co-extensive with the complete plurality of cathode vanes for cooperating therewith, and means for heating the base member.

4. An electric-discharge device having a plurality of electrodes including an anode and a cathode spaced from one another along a predetermined direction within an ionizable medium, the cathode comprising a base member carrying a plurality of spaced annular vanes having electron-emitting surfaces extending substantially along the predetermined direction from the base member and extending substantially completely across the base member, the anode having a surface co-extensive with the complete plurality of cathode vanes for cooperating therewith, and means for heating the base member.

5. An electric-discharge device having a plurality of electrodes including an anode and a cathode spaced from one another along a predetermined direction within an ionizable medium, the cathode comprising a base member carrying a plurality of substantially concentric cylindrical vanes having electron-emitting surfaces extending substantially along the predetermined direction from the base member and extending substantially completely across the base member, the anode having a surface co-extensive with the complete plurality of cathode vanes for

cooperating therewith, and means for heating the base member.

6. An electric-discharge device having a plurality of electrodes including an anode and a cathode spaced from one another along a predetermined direction within an ionizable medium, the cathode comprising a base member carrying a plurality of honey-comb-arranged vanes having electron-emitting surfaces extending substantially along the predetermined direction from the base member and extending substantially completely across the base member, the anode having a surface co-extensive with the complete plurality of cathode vanes for cooperating therewith, and means for heating the base member.

7. In an electric discharge device, a cathode comprising a base member carrying a plurality of substantially parallel thin cathode elements each having electron-emitting surfaces extending substantially completely across and extending normal to the base and separated from one another by a spacing of the order of substantially one-to-two millimeters.

8. In an electric discharge device, a cathode comprising a base member carrying a plurality of substantially parallel thin cathode elements each having electron-emitting surfaces extending substantially completely across and extending normal to the base and separated from one another by a spacing of the order of substantially one-to-two millimeters, and means for heating the base member.

9. A gaseous-discharge device having a plurality of electrodes including an anode and a cathode spaced from one another along a predetermined direction within a hydrogen-gas medium, the cathode comprising a base member carrying a plurality of spaced vanes having electron-emitting surfaces extending substantially along the predetermined direction from the base member and extending substantially completely across the base member, the anode having a surface co-extensive with the complete plurality of cathode vanes for cooperating therewith, and means for heating the base member.

10. An electric-discharge device having a plurality of electrodes including an anode and a cathode spaced from one another along a predetermined direction within an ionizable medium, the cathode comprising a base member carrying a plurality of spaced vanes having electron-emitting surfaces extending substantially along the predetermined direction from the base member and extending substantially completely across the base member, the anode having a surface co-extensive with the complete

plurality of cathode vanes for cooperating therewith, and means for heating the cathode.

11. In an electric-discharge device, a cup-shaped cathode containing a substantially flat base member carrying a plurality of spaced conductive vanes having electron-emitting surfaces extending in a direction toward the opening of the cup and extending substantially completely across the said opening, and means for heating the cathode.

12. In an electric-discharge device, a cathode comprising a base member carrying a plurality of substantially planar sections each having electron-emitting substantially planar surfaces extending substantially normal to the base member and extending substantially completely across the base member.

13. In an electric-discharge device, a cathode comprising a base member carrying a plurality of substantially planar sections each having electron-emitting substantially planar surfaces extending substantially completely across the base member and extending substantially normal to the base a distance L given substantially by the equation

$$L = \frac{1}{2} \sqrt{\frac{2i_T R_0}{P \left(E_p - \frac{dV_s}{dx} \right)}}$$

where i_T is the current passed through the discharge device from the cathode, E_p is the electric field acting upon the cathode, V_s is the potential drop across the cathode sheath

$$\frac{dV_s}{dx}$$

is the potential gradient in the cathode sheath and P is the total perimeter of the cathode.
